CLAIM

The ornamental design for a paper trimmer for tearing away edges of perforated computer paper, as shown and described.

DESCRIPTION

FIG. 1 is a top, left front perspective view of a paper trimmer for tearing away edges of perforated computer paper showing my new design, with the cover member in an opened condition;

FIG. 2 is a top, left front perspective view with the cover member in a closed condition;

FIG. 3 is a top plan view of FIG. 2;

FIG. 4 is a bottom plan view of FIG. 2;

FIG. 5 is a left side elevational view of FIG. 2;

FIG. 6 is a front elevational view of FIG. 2;

FIG. 7 is a right side elevational view of FIG. 2; and,

FIG. 8 is a rear elevational view of FIG. 2.

FIG. 1.FIG. 2.FIG. 3.FIG. 4.FIG. 5.FIG. 6.FIG. 7.FIG. 8.
